DRAFT RIGGING

Filed Jan. 27, 1932

Inventor

Charles E. Dath

Charles E. Dahn
By Henry Fuchs, Atty.

UNITED STATES PATENT OFFICE

CHARLES E. DATH, OF CHICAGO, ILLINOIS, ASSIGNOR TO W. H. MINER, INC., OF CHICAGO, ILLINOIS, A CORPORATION OF DELAWARE

DRAFT RIGGING

Application filed January 27, 1932. Serial No. 589,140.

This invention relates to improvements in draft riggings especially adapted for use in connection with mine cars.

One object of the invention is to provide simple and efficient means for absorbing both the draft and buffing shocks to which mine cars are subjected, said means being in the form of a single shock absorbing device comprising a plurality of transversely arranged spring plate members at each end of the car, to the opposite ends of which the buffing forces are transmitted, thereby flexing the plate members to cushion buffing shocks.

Another object of the invention is to provide in a draft rigging of the character indicated in the preceding paragraph simple means for connecting the coupler element to the car by the use of a transverse beam member at each end of the car, which beam member also serves as a cushioning means for both draft and buffing shocks, the beam member being fabricated of flexible resilient material in the form of a gang of plates to produce this result.

Other objects of the invention will more clearly appear from the description and claims hereinafter following.

In the drawing, forming a part of this specification, Figure 1 is a part plan and part horizontal, sectional view of one end of a mine car, illustrating my improvements in connection therewith. Figure 2 is a longitudinal, vertical, sectional view, corresponding substantially to the line 2-2 of Figure 1. Figure 3 is an elevational view, partly broken away, looking from the left in Figure 1. And Figure 4 is a longitudinal, vertical, sectional view, corresponding substantially to the line 4-4 of Figure 1.

In said drawing, A designates generally the end portion of a mine car, it being understood that the mine car is of the usual design having opposite ends thereof formed similarly. The end of the car is provided with the usual transverse sill member 10, which extends from side to side of the car. My improved shock absorbing mechanism is mounted on the end sills at opposite ends of the car and is so arranged as to serve as cushioning means for buffing shocks imparted to

buffing heads at opposite sides of the car and draft shocks imparted to the cushioning means through a centrally disposed coupling element. The end sill 10 has a pair of spaced supporting castings or housings 11-11 fixed thereto. The two housings 11 are of similar design, each having a transverse, vertical front end wall 12, side walls 13 and 14, and top and bottom walls 15 and 16. At the inner side of each casting, the walls 13 and 14 are provided with laterally extending securing lugs or flanges 17-17, which are fixed to the sill 10 by any suitable securing elements, such as rivets extending through these flanges and the vertical web of the sill 10. The wall 14, which is on the inner side of the casting 11, is provided with an opening 18 for a purpose hereinafter pointed out. The outer wall 12 has the inner side thereof curved at said opening, as indicated at 19. The inner wall of the opening 18 is laterally thickened, as clearly shown in Figure 1, said thickened portion presenting a curved bearing or abutment surface 20, which is disposed laterally inwardly of the car with respect to the abutment face or surface 19 of the wall 12 of the casting. The front wall 12 is also provided with a central guide opening 21 adapted to form guide means for the corresponding buffing head hereinafter more fully described. Outwardly of the wall 12, the top and bottom walls 15 and 16 of the casting extend forwardly and are connected by spaced vertical walls 22-22, the latter, together with the top and bottom wall sections outwardly of the wall 12, forming a continuation of the guideway 21. As most clearly shown in Figure 1, the top and bottom walls 15 and 16 are centrally offset, as indicated at 23-23, inwardly of the wall 12 to present top and bottom guide channels in alignment with the guide faces formed by the top and bottom walls 15 and 16 outwardly of the wall 12.

A pair of buffing heads 24-24 are arranged at opposite sides of the end of the car, each head having a rearwardly extending stem 25 guided in the guide opening 21 and the guideway formed by the walls inwardly and outwardly of said opening. At the inner end, the stem 25 of each buffing head

24 is provided with a transverse opening 26 having front and rear curved bearing walls 27-27. A plurality of spring plates are employed as the shock absorbing means, said plates being arranged transversely of the mechanism. As clearly shown in Figures 1, 2, and 4, the gang is preferably composed of four spring plates 28-28. The opposite ends of the gang of plates extend into the two housings respectively and are engaged through the openings 26-26 of the stems of the buffering heads 24-24 respectively. The outer ends of the plates 28-28 preferably project beyond the corresponding buffering stems. A coupler hook 29 is connected to the gang of spring plates midway between the ends of the same, said hook being provided with a laterally enlarged shank portion 30 having a transverse opening 31, through which the plates 28-28 are engaged. The rear wall of the opening 31 is curved, as indicated at 32, while the front wall of the same is preferably flat.

25 In the operation of my improved draft rigging, assuming that a pulling action is applied to the coupler hook 29, the latter will be pulled outwardly away from the car, thereby bowing the gang of spring plates outwardly. During this action, the spring plates are supported at opposite ends on their outer sides by the abutment surfaces 19-19 of the front walls 12-12 of the castings 11-11. As will be evident, the draft shocks are thus yieldingly cushioned by the flexing of the gang of spring plates. In addition to offering spring resistance to shocks, the plates also provide a certain amount of frictional resistance due to relative sliding movement of the plates on each other during flexing thereof.

Upon a buffering force being applied to either or both of the buffering heads 24, the heads will be moved inwardly toward the car. 45 Inward movement of each head 24 causes inward flexing of the corresponding end of the gang of spring plates, thus effectively cushioning the shocks. The spring plates while being flexed inwardly at opposite ends by the buffering members are supported on the curved bearing surfaces 20-20 of the inner end walls of the openings 18-18 of the castings 11-11.

From the preceding description taken in 55 connection with the drawing, it will be evident that I have provided an exceedingly simple and efficient flexible connection for mine cars, which serves to cushion draft shocks and also by the same cushioning means 60 takes care of buffering shocks transmitted to the buffering members at opposite sides of the car. The improved shock absorbing mechanism may be readily applied to any well-known construction of mine cars without alteration of the car underframe structure, it

being necessary merely to secure the two housing castings and the other parts assembled therewith to the end sill of the car.

I have herein shown and described what I now consider the preferred manner of carrying out my invention, but the same is merely illustrative and I contemplate all changes and modifications that come within the scope of the claims appended hereto.

I claim:

1. In a draft rigging for cars, the combination with a transversely disposed gang of spring plates connected to the end of the car; of spaced abutment means on the car supporting the gang of plates on the inner side thereof at points inwardly of the outer ends of said gang of plates; a coupler element connected to said spring plates between said abutments; and inwardly movable means for transmitting buffering forces to opposite ends of said gang of spring plates, said last named means including members at opposite sides of the same end of the car bearing on the opposite end sections of said gang of plates at points laterally outwardly of said spaced abutment means to flex said plates in buff, thereby cushioning the shocks.

2. In a draft rigging for cars, the combination with a transversely disposed, resilient, flexible member connected to the end of the car; of supports on the car at laterally spaced points opposing outward movement of the flexible member; a coupler element connected to said member between said spaced points, whereby said member is flexed outwardly upon a pulling action being applied to the coupler to cushion draft shocks; and inwardly sliding buffering heads engaged with the opposite ends of said flexible member to bend said ends inwardly upon inward movement of said heads to cushion buffering shocks.

3. In a draft rigging for cars, the combination with a transversely disposed, resilient, flexible member connected to the end of the car; of supports on the car at laterally spaced points opposing outward movement of the flexible member; a coupler element connected to said member between said spaced points, whereby said member is flexed outwardly upon a pulling action being applied to the coupler to cushion draft shocks; laterally spaced abutment means on said car engaging the inner sides of said flexible member at laterally spaced points; and inwardly movable buffering heads engaging opposite end portions of said flexible member at points laterally offset with respect to said spaced abutment means, whereby said member is flexed upon inward displacement of said buffering heads to thereby cushion buffering shocks.

4. In a draft rigging for cars, the combination with a transversely disposed, resilient,

- flexible member connected to the end of the car; of supports on the car at laterally spaced points opposing outward movement of the flexible member; a coupler element connected 5 to said member between said spaced points, whereby said member is flexed outwardly upon a pulling action being applied to the coupler to cushion draft shocks; laterally spaced abutment means on said car engaging 10 the inner sides of said flexible member at laterally spaced points; and inwardly movable buffing heads engaging opposite end portions of said flexible member at points laterally outwardly offset with respect to said 15 spaced abutment means, whereby said ends of the member are flexed inwardly upon displacement of said buffing heads to cushion buffing shocks.
5. In a draft rigging for cars, the combination with a transversely disposed, resilient, flexible member connected to the end of the car; of supports on the car at laterally spaced points opposing outward movement of the flexible member; a coupler element 20 connected to said member between said spaced points, whereby said member is flexed outwardly upon a pulling action being applied to the coupler to cushion draft shocks; spaced abutment means on the end of the car offset 25 respectively laterally outwardly of said supports and engaging the inner side of the flexible member; and inwardly movable buffing heads at opposite sides of the same end of the car bearing on the ends of said flexible 30 member at points laterally outwardly of said spaced abutment means respectively.
6. In a draft rigging for cars, the combination with a transversely disposed gang 35 of spring plates connected to the end of the car; of supports at laterally spaced points on the car engaging said gang of spring plates and opposing outward movement thereof; a coupler element connected to said gang of plates between said spaced points, 40 whereby said plates are flexed outwardly upon a pulling action being applied to the coupler to cushion draft shocks; and inwardly sliding buffing heads engaging with the opposite ends of said gang of spring plates to 45 bend said ends inwardly upon inward movement of said head to cushion buffing shocks.
7. In a draft rigging for cars, the combination with a transversely disposed gang 50 of spring plates connected to the end of the car; of supports at laterally spaced points on the car engaging said gang of spring plates and opposing outward movement thereof; a coupler element connected to said 55 gang of plates between said spaced points, whereby said plates are flexed outwardly upon a pulling action being applied to the coupler to cushion draft shocks; laterally spaced abutment means on said car engaging the inner side of said gang of plates at laterally spaced points; and inwardly movable buffing heads engaging opposite end portions of said gang of plates at points laterally offset with respect to said spaced abutment means, whereby said plates are flexed upon inward displacement of the buffing heads to cushion buffing shocks. 70
8. In a draft rigging for cars, the combination with a transversely disposed gang 75 of spring plates connected to the end of the car; of supports at laterally spaced points on the car engaging said gang of spring plates and opposing outward movement thereof; a coupler element connected to said gang of plates between said spaced points, whereby said plates are flexed outwardly upon a pulling action being applied to the coupler to cushion draft shocks; laterally spaced abutment means on said car engaging the inner side of said gang of plates at laterally spaced points; and inwardly movable buffing heads engaging opposite end portions of said gang of plates at points laterally offset with respect to said spaced abutment means, whereby said plates are flexed upon inward displacement of the buffing heads to cushion buffing shocks. 80
9. In a draft rigging for cars, the combination with a transversely disposed gang 85 of spring plates connected to the end of the car; of supports at laterally spaced points on the car engaging said gang of spring plates and opposing outward movement thereof; a coupler element connected to said gang of plates between said spaced points, whereby said plates are flexed outwardly upon a pulling action being applied to the coupler to cushion draft shocks; laterally spaced abutment means on said car engaging the inner side of said gang of plates at laterally spaced points; and inwardly movable buffing heads engaging opposite end portions of said gang of plates at points laterally offset with respect to said spaced abutment means, whereby said plates are flexed upon inward displacement of the buffing heads to cushion buffing shocks. 90
10. In a draft rigging for cars, the combination with a transversely disposed gang 95 of spring plates connected to the end of the car; of supports at laterally spaced points on the car engaging said gang of spring plates and opposing outward movement thereof; a coupler element connected to said gang of plates between said spaced points, whereby said plates are flexed outwardly upon a pulling action being applied to the coupler to cushion draft shocks; laterally spaced abutment means on said car engaging the inner side of said gang of plates at laterally spaced points; and inwardly movable buffing heads engaging opposite end portions of said gang of plates at points laterally offset with respect to said spaced abutment means, whereby said plates are flexed upon inward displacement of the buffing heads to cushion buffing shocks. 100
11. In a draft rigging for cars, the combination with a transversely disposed gang 105 of spring plates connected to the end of the car; of supports at laterally spaced points on the car engaging said gang of spring plates and opposing outward movement thereof; a coupler element connected to said gang of plates between said spaced points, whereby said plates are flexed outwardly upon a pulling action being applied to the coupler to cushion draft shocks; laterally spaced abutment means on the end of the car offset respectively laterally outwardly of said supports and engaging the inner side of said gang of plates; and inwardly movable buffing heads at opposite sides of the same end of the car bearing on the ends of said gang 110 of plates at points laterally outwardly of said spaced abutment means respectively. 115
12. In witness that I claim the foregoing I have hereunto subscribed my name this 25th day of January, 1932. 120

CHARLES E. DATH.
